(57) **CLAIM**

The ornamental design for a vehicle rear exhaust support, as
shown and described.

DESCRIPTION

FIG. 1 is a rear view of the vehicle rear exhaust support
according to the present design;

FIG. 2 is a top view of the vehicle exhaust support as
generally illustrated in FIG. 1;

FIG. 3 is a front plan view of the vehicle exhaust support;
FIG. 4 is a bottom view of the vehicle exhaust support; and,
FIG. 5 is a first side view of the vehicle support, a corre-
sponding second side view being a mirror image thereof.

The broken lines shown in the drawing are for illustrative
purposes only and form no part of the claim design.
